United States Patent Office

Des. 215,280

Patented Sept. 23, 1969

215,280

CHAIR

Wayland B. Parker, South Boston, Va., assignor to Schlumberger Limited (Schlumberger N.V.), New York, N.Y., a corporation of the Netherlands Antilles

Filed May 8, 1968, Ser. No. 11,834

Term of patent 14 years

Int. Cl. D6—01

U.S. Cl. D15—1

The dominant features of my design reside in those portions shown in full lines on the drawing.

I claim:

The ornamental design for a chair, substantially as shown and described.
